UNITED STATES PATENT OFFICE.

JACQUES PIERRE DE BRAAM, OF PARIS, FRANCE.

RECORDER FOR SIGNALS AND ENGINE-DRIVERS.

SPECIFICATION forming part of Letters Patent No. 708,993, dated September 16, 1902.

Application filed April 21, 1902. Serial No. 103,986. (No model.)

To all whom it may concern:

Be it known that I, JACQUES PIERRE DE BRAAM, of No. 30 Rue Hamelin, Paris, in the Republic of France, have invented a certain 5 new and useful Device for Recording the Position of Signals and the Operations of the Engine-Driver While Trains are Passing the Signals; and I do hereby declare the following to be a full, clear, and exact description 10 of the invention, such as will enable others skilled in the art to which it appertains to make and use the same.

The invention consists in the features and combination and arrangement of parts hereinafter described, and particularly pointed 15 out in the claims.

I have myself described in a former British patent, No. 7,626, April 13, 1901, a special 20 warning apparatus, and I will now describe as a representative example a new recording contrivance arranged as combined with the aforesaid warning apparatus.

My invention is shown in detail on the accompanying drawings, in which—

25 Figure 1 is a front view of the recording-apparatus mounted on the locomotive and fixed onto a box *c*, which forms part of the special warning apparatus described in my previously-mentioned patent. Fig. 2 is a corresponding side elevation. Fig. 3 is an elevation as seen from the opposite side to that of Fig. 1. Fig. 4 is a side elevation as seen from the opposite side to that of Fig. 2. Fig. 5 represents in plan a sheet of the impressions taken from the recording-roller.

The recording arrangement is set in motion by any suitable transmitting device—in this particular example by the cam *a*. The cam *a* is mounted on an axis *b*, mounted in the 40 box *c* and which carries the arrangements of the warning apparatus. On this box for the sake of compactness can be fixed the registering apparatus, properly speaking, which is the subject of the present demand for a 45 patent. This apparatus is composed in principle, on the one hand, of a tracing-pointer *d*, which is normally held out of contact and is brought into contact each time this cam is put in motion for the working of the warning apparatus when passing either of the 50 raised signals "Proceed with caution" or "Stop" and, on the other hand, of a roller *e*,

carrying paper, Figs. 2 and 3, which is put in motion by a clockwork mechanism. This is normally at rest and is set in motion at the 55 same time as the tracing-pointer is brought into a position for marking by the action of the same transmitting-gear or of the intermediate parts in connection with it. It is apparent that under these conditions the 60 paper carried on the roller *e* will receive a particular impression every time the train passes a raised signal "Proceed with caution" or a signal "Stop." On the contrary, the paper remains free of all impressions if 65 the two signals are both down when the train passes. The inscriptions on the roller thus record the position (down or up) occupied by the various signals along the route of the train carrying this apparatus. On the other 70 hand, the operations of the engine-driver while passing the signals are also recorded, since the paper registers a line more or less long according as after passing a raised signal "Proceed with caution" the engine-driver is more or less slow in stopping the 75 working of the warning apparatus by replacing the latter in its normal position, and then also the paper either does or does not record a second line according as the engine-driver has stopped the train either beyond or before reaching the raised signal "Stop."

In the particular form of construction shown the tracing-pointer *d* is fixed to a plate *f*, pivoted on an axis *g*, carried by the frame 85 *h* of the apparatus. A flat spring *i*, fixed to the frame in contact with the plate *f*, tends to constantly press it down and cause the pointer *d* to make contact with the paper carried by the roller *e*. Normally—that is to 90 say, when the train is progressing unrestricted with the warning apparatus at rest—the plate *f* is held in a raised position by the upper end of a rod *j*, which is guided in a sleeve *k* and terminated at its lower end by a slot-way *l*, into which is inserted one of the arms *m* of a double lever *m n*, of which the other arm *n* has its end in constant contact with the cam *a*. This lever *m n* is pivoted on the fixed axis *o*, carried by the casing *c*. A 100 spring *p* surrounds the rod *j* and is fixed by one of its ends to the guide *k* and presses its other end against a collar *q*, formed on the rod *j*. It thus tends to constantly raise the rod *j*,

and consequently the plate *f*. It goes without saying that the tension of the spring *p* should be enough to overcome the resistance of the spring *i*.

5 Figs. 1, 2, and 3 represent the mechanism in its normal position, the guiding-cam *a* of the warning apparatus being at rest. In this position the tracing-pointer *d* is removed from the roller *e*, and this latter is held at 10 rest by the engagement of one of the recesses on the wheel *r* of the clockwork mechanism with one of the arms *s* of a two-armed lever *s t*, of which the other arm *t* is kept down to the same degree that the plate *f* itself is kept 15 raised. Normally the arm *t* is kept down by one of the arms *u* of a double lever *u v*, pivoted to the frame *h*, the other arm *v* of this lever being subject to the action of a spring *x*, fixed to this same frame. The two-armed 20 lever *s t* is itself pivoted at *w* to the frame *h*, and its arm *s* carries at its extremity a spur *y*, which engages with a notch on a disk *r*. The spur *y*, which normally remains engaged 25 with the disk *r*, is released from this latter when the hook *z*, formed on the end of the arm *l*, of the plate *f* raises the arm *t* of the lever *s t*. This movement is produced when the rod *j* descends and allows the spring *i* to 30 press down the plate *f*. It goes without saying that the tension of the spring *x* is necessarily weaker than that of the spring *i*. It is thus seen that normally the clockwork mechanism which actuates the roller *e* remains motionless so long as the tracing-pointer *d* is not lowered and is set in motion 35 when this pointer *d* is lowered. This clockwork mechanism, which may be of any known construction, is in the example shown made as follows: On a spindle 3, carried on the 40 frame *h*, is mounted a drum 2, on the end of which is fixed a toothed wheel 4. This latter gears with a pinion 5, mounted on the axis 6, which carries the engaging disk *r*. On this same axis the wheel 7 is keyed, and 45 this gears with the wheel 8, which is mounted on the same axis 9 as that which carries the roll of paper *e*. The movement of the roller *e* is effected by the wheel 8 by means of a rod 10, fixed on this wheel parallel to the 50 axis 9 and passing through the roller from one end to the other. The roller receives simultaneously with the rotary movement a forward longitudinal movement. It carries for this purpose an endless screw 11, which is 55 in gear with a toothed rack 12, conveniently fixed onto the frame *h*, Fig. 3. While turning with the wheel 8 the roller *e* glides along the rod 10 and on the axis 9. At every complete turn of the wheel 8 and the roller *e* this 60 latter is displaced longitudinally the distance of the pitch of one tooth of the toothed rack 12. The proportions of the clockwork mechanism are so calculated that the roller *e* completes one revolution and advances one tooth 65 in about three minutes. During this time a train running at the mean rate of sixty kilometers an hour will traverse a distance of

three kilometers, which is more than the greatest distance between a signal "Proceed with caution" and the next signal "Stop." 70 Let us suppose the mechanism to be in the position shown in the several figures of the drawings and the roller *e* covered by a sheet of paper of which Fig. 5 represents the development. Cam *a* of the warning apparatus is then at rest in the position indicated. If on the journey the engine-driver does not meet any signal against him, the actuating-lever of the warning apparatus will not encounter any striker, and the mechanism of 80 the warning apparatus, as well as that of the recording apparatus, will remain at rest, in which case at the end of the journey the paper on the roller *e* will be free from all inscription. Let us now imagine that the train 85 passes a raised signal "Proceed with caution," the striking-lever corresponding to this signal will be raised and will set in motion the depending lever of the warning apparatus. Cam *a* will turn in the direction of the arrow, 90 Figs. 1 and 3, and will complete about one-eighth of a revolution in such a way that the projection 13, coming in contact with the arm *n*, causes the two-armed lever *m n* to turn, so that its arm *m* pulls the rod *j* downward. 95 The spring *p* is compressed, and the upper end of the rod *j* by releasing the plate *f* allows the spring *i* to press down the tracing-pointer *d* into contact with the roller *e*. At the same time the plate *f* in sinking causes 100 the hook *z* to rise. This causes the double lever *s t* to move and release the spur *y* from the disk *r* and sets the clockwork mechanism at work. The arm *u* of the double lever *u v* is also lifted by the end of the arm *t*. The end 105 of the arm *v* thus frees the regulating fly-wheel 14, which is supported on an axis carried by the frame. An endless screw 16 is by a series of suitable gearings in connection with the toothed circumference 4 of the barrel 2. This 110 latter in turning causes the wheel 8 to revolve by means of the wheels 5 and 7, which in its turn, with the aid of the rod *j*, gives motion to the roller *e*. So long as the cam *a* remains in the position into which it was 115 driven by the working of the warning apparatus the clockwork mechanism works, and the pointer *d* will trace a helix 17 on the surface of the paper. When the engine-driver by 120 paying proper attention to the warning apparatus replaces the cam *a* in its original position, (which operation can be performed by means of a lever secured to the axis *b*,) the spring *p*, pressing against the collar *g*, will return the rod *j* to its original position, removing by the same means the pointer *d* from 125 the roller *e*. The latter continues to revolve until a notch in the disk *r* engages with the spur *y*. The roller thus makes an entire revolution, corresponding to a journey of 130 three kilometers at the lowest speed of sixty kilometers an hour. If we imagine the case in which the engine-driver has simply passed a raised signal "Proceed with caution" and

has stopped the train before reaching the raised signal "Stop" or, better still, has passed this signal not raised, the paper only bears the trace of a straight line 17, (the development of the helix described by the end of the pointer *d*,) from the length of which can be judged approximately the distance run by the train between the instant when it passed the raised signal "Proceed with caution" and the precise moment when the engine-driver replaced the warning apparatus to its original position. Let us imagine that having passed a raised signal "Proceed with caution" and having returned the warning apparatus at the end of a certain time (less than the time it takes to pass between the two signals) into its original position, the engine-driver neglecting the warning received passes the raised signal "Stop," the depending lever of the warning apparatus then encounters the striker corresponding to this signal "Stop" and the axis *b* receives an angular displacement such that the flat side 18 of the cam *a* comes in contact with the arm *n*. Since before the cam could arrive in this position, its projection 13 must in passing actuate the arm *n*, and thus cause a temporary lowering of the pointer *d*. Also since the roller *e* will be still in motion, having been started by the first movement of the warning apparatus while passing the raised signal "Proceed with caution" and not having yet completed its revolution, it will receive at the time when the pointer is temporarily lowered a new impression. The time during which the pointer is lowered is so short that this impression is reduced to a clearly-marked dot. If the paper of the roll be then examined, it bears in this second hypothetical case traces 19 and 20, Fig. 5. Trace 19 indicates, as in the preceding case, that the signal "Proceed with caution" was raised and that the engine-driver passed this signal and returned the warning apparatus to its normal position after it had worked for a time the duration of which is easy to determine from the length of the line 19. On the other hand, the dot 20 shows that the engine-driver had gone on and passed the signal "Stop," which was also raised. The responsibility of the engine-driver is thus clearly established. He will not be able to attribute his mistake to the negligence of the signalman, since it follows that the two consecutive signals ("Proceed with caution" and "Stop") must have been up for the register to bear the marks 19 and 20. Finally, let us consider a third case: The signalman while raising the signal "Stop" has neglected to raise the signal "Proceed with caution" immediately preceding it. In this case the engine-driver naturally passes the depressed signal "Proceed with caution," and the warning apparatus, as well as the registering apparatus, remains at rest. If under these conditions the train continuing its progress passes the raised signal "Stop," there results as before

a temporary lowering of the pointer *d* and a simultaneous starting of the clockwork mechanism. The roller *e* makes its complete revolution; but the paper only bears the trace of the dot 21, which reveals incontestably the mistake made by the signalman. To sum up, the paper can bear three kinds of impressions, all starting from an initial line 22. This line is always found slightly on this side of the pointer *d* when the roller is at rest or when it has returned to its original position after having made a complete revolution.

First. A simple straight line 17, quite short, shows that the engine-driver has passed a raised signal "Proceed with caution" and that he has taken notice of the warning apparatus by stopping his train before reaching the raised signal "Stop." In the case when this line is of a length corresponding with a revolution or of a length such that the corresponding distance traveled by the train exceeds the distance between the two signals "Proceed with caution" and "Stop" the culpability of the engine-driver is thus registered and established.

Second. A straight line 19 followed at some distance by the dot 20 indicates that the engine-driver first passed a raised signal "Proceed with caution," that he stopped the working of the warning apparatus, and that without heeding the warning received he passed the next raised signal "Stop." The culpability of the engine-driver will thus in this case also be established.

Third. A simple dot 20 indicates that the engine-driver has passed a raised signal to "Stop;" but it shows at the same time that the warning apparatus has not been set in motion while passing the signal "Proceed with caution," and so this latter must have been down. Even if in the meantime the signalman seeing his mistake and wishing to hide it by raising after the train has passed the signal "Proceed with caution," which he had neglected to raise at first, his deceit will be clearly established and registered.

It goes without saying that the details of construction of a registering device such as I have just described may be varied without altering the principle of my invention. The apparatus may also be provided with extra mechanisms, such as a winding-gear 23 24 and a revolution-counter 26.

I claim—

1. In combination with a moving vehicle, a record-cylinder, a motor for rotating the same, means for holding the cylinder normally against rotation, a marker adapted to contact with said cylinder, means carried by the vehicle for simultaneously releasing said holding means and lowering the marker, and means for imparting an endwise movement to said cylinder while it is rotating, substantially as described.

2. In combination with a moving vehicle, a record-cylinder, a motor for rotating the same, means for imparting to said cylinder an end-

wise movement when rotating, a pivoted spring-pressed plate carrying a marker adapted to make contact with said cylinder, a rod normally holding said plate out of contact with the cylinder, means for depressing said rod, and means controlling the movement of the motor, substantially as described.

3. In combination with a vehicle, a cylinder, a motor for rotating the same, a spring-pressed arm carrying a pointer adapted to contact with said cylinder, a rod having its upper end beneath said plate, a spring for forcing said rod upwardly, a bell-crank lever having one arm engaging said rod, and a rotatable cam adapted to operate against the other arm, substantially as described.

4. In combination with a moving vehicle, a record-cylinder, a shaft supporting the same, means for rotating said cylinder, a marker for said cylinder, a screw on one part of said cylinder, a stationary rack engaging said screw, and means for controlling both the operation of the marker and movement of the cylinder, substantially as described.

In testimony that I claim the foregoing as my invention I have signed my name in the presence of two subscribing witnesses.

JACQUES PIERRE DE BRAAM.
